FIG. 1.

FIG. 2.

FRED D. FULTON,
INVENTOR.

BY Orville R. Leidner

UNITED STATES PATENT OFFICE

171,849

LAZY SUSAN

Fred D. Fulton, Duarte, Calif.

Application July 30, 1953, Serial No. 26,198

Term of patent 7 years

(Cl. D44—10)

To all whom it may concern:

Be it known that I, Fred D. Fulton, a citizen of the United States, residing at Duarte, in the county of Los Angeles and State of California, have invented a new, original, and ornamental Design for a Lazy Susan, of which the following is a specification, reference being had to the accompanying drawing, forming part thereof, and wherein.

Fig. 1 is a perspective view of a Lazy Susan, showing my new design; and

Fig. 2 is a side elevational view thereof; a portion of which is shown in cross-section.

I claim:

The ornamental design for a Lazy Susan, as shown.

FRED D. FULTON.
